UNITED STATES PATENT OFFICE.

CLARENCE H. MAXWELL AND CHARLES C. HIMES, OF INDIANAPOLIS, INDIANA.

DOMESTIC BOILER.

Application filed August 5, 1927. Serial No. 210,761.

This invention relates to a domestic wash boiler.

The chief object of the invention is to construct a boiler in such a manner that the 5 same will in normal operation never boil or overflow.

The chief feature of the invention consists in the formation of the boiler by the addition of a peripheral deflector secured to the 10 side wall of the boiler adjacent the removable cover mounting and extending inwardly and upwardly within said boiler for deflecting the boiling fluid from the cover connection thereby permitting the boiler to be 15 heated at a greater rate than heretofore possible without overboiling.

The full nature of the invention will be understood from the accompanying drawings and the following specification and 20 claim:

Fig. 1 is a side elevational view of the invention. Fig. 2 is a similar view of a modified form of the invention, the cover being removed.

25 In the drawings 10 indicates the bottom of a boiler connected to which is a side wall 11 having the beaded mouth 12 and the usual supporting handles 13. A cover 14 is provided with a handle 15 and the cover includes the telescoping peripheral flange 16 and the lateral peripheral flange 17 for forming a relatively tight joint.

Secured to the side wall 11 and near the mouth thereof is a deflector or baffle, the 35 lower portion 18 of which extends inwardly and upwardly. An upper portion and return ledge 19 directed inwardly and downwardly, is also provided for securing continuity of surface from the inner edge of the 40 inwardly and upwardly extending portion of the baffle to the depending cover flange 16. The cover flange 16 nests within the boiler and flange 17 rests on the boiler bead 12.

The operation of the device is as follows: 45 The fluid such as water, is put into the boiler together with the articles to be boiled such as clothing and the like, and the water is boiled. As the steam including the lather is generated the same passes upwardly but that 50 which passes upwardly along the side wall 11 is deflected inwardly into the cover portion and thereafter is deflected downwardly thereby so that boiling over is prevented and the desired turbulence is secured within the 55 boiler. This predetermined turbulent condition throughout the boiler contents permitted by the nonspilling action results in the automatic washing or cleansing of the clothing.

In Fig. 2 a modified form of the invention is illustrated and in this form of the invention the boiler 110 includes a side wall 111 which terminates in the beaded mouth 112, but herein the beaded mouth 112 is connected to the side wall 111 adjacent the beaded mouth by the peripheral side forming and ledge forming portions 118 and 119 substantially the full equivalent of the modification disclosed in Fig. 1.

70 The invention claimed is:

A boiler having a side wall and a self-draining baffling ledge comprising a reversely curved deflector portion arranged peripherally around the side wall in spaced 75 relation to the top of the side wall, the lower and baffle portion being inwardly and upwardly directed and the upper ledge portion being inwardly and downwardly directed with the junction of said portions at an appreciable distance from the wall within the 80 boiler.

In witness whereof, we have hereunto affixed our signatures.

CLARENCE H. MAXWELL.
CHARLES C. HIMES.
